UNITED STATES PATENT OFFICE.

OTIS L. LONGWORTH, OF DETROIT, MICHIGAN, ASSIGNOR OF ONE-HALF TO A. L. McCORMICK, OF DETROIT, MICHIGAN.

SPARK-PLUG.

1,350,319.

Specification of Letters Patent. Patented Aug. 24, 1920.

Application filed September 27, 1919. Serial No. 326,839.

To all whom it may concern:

Be it known that I, OTIS L. LONGWORTH, a citizen of the United States of America, residing at Detroit, in the county of Wayne 5 and State of Michigan, have invented certain new and useful Improvements in Spark-Plugs, of which the following is a specification, reference being had therein to the accompanying drawings.

10 This invention relates to spark plugs and its object is to provide a spark plug having a spark gap located within a chamber, which may be formed by the casing of the plug and which will protect the electrode 15 forming said gap from such drops of lubricating oil as may be thrown off from the piston of the engine.

A further object of the invention is to provide a spark plug having two spark 20 gaps one of which is formed between the end portion of the usual central electrode and a hood portion of the casing of the plug, the second gap being formed within a chamber of the casing partially closed by 25 said hood, the hood acting additionally to shield the electrode of said second spark gap from such lubricating oil as may be thrown off from the piston of the engine, so that when the first mentioned gap becomes 30 inoperative by reason of said oil the gap within said chamber will come into use.

A preferred embodiment of the invention is hereinafter described as illustrated in the accompanying drawings.

35 Figure 1 is an axial sectional view of the improved plug;

Fig. 2 is an end view of the same.

In these views the reference character A designates the porcelain of the plug, B the 40 stem passing through said porcelain and forming a central electrode and C the casing within which said porcelain is secured. A spark gap D is formed between a reduced end portion E of the stem B and a hood F of 45 approximately semi-spherical shape upon the inner end of the casing C and preferably integral with said casing. The aperture of the hood F forming said gap is circular so that there are innumerable points at which 50 the spark may cross said gap. Thus the possibility of fouling of the electrodes by carbonization or lubricating oil is minimized. Between the hood F and porcelain A there is formed a chamber G, to which the 55 gases in the combustion chamber (not

shown) have access through several orifices H in the hood F, as well as through the gap D. Within said chamber a second spark gap J, slightly wider than the gap D, is formed between the casing C and an electrode K formed as a collar upon the stem B and preferably integral with said stem. 60

In the operation of the described invention the spark will occur at the gap D if the electrodes forming said gap are not 65 fouled by a lubricating oil, since this gap is of lesser width than that at J. If, however, the presence of lubricating oil upon the electrode at D prevents the passage of a spark, this does not render the plug inoperative since sparking will then occur at J. Except under very extraordinary conditions, the electrodes forming the gap D will not be fouled by a lubricating oil owing to the protection afforded by the hood F. 70 Because of the circular form of the gap J and its relatively large diameter, even if lubricating oil penetrates to some extent to the chamber G, it is altogether improbable that the electrodes forming the gap J will be 80 completely fouled by such oil. Because of the periodic rush of gases to and from the chamber G, there can be no accumulation of carbon upon the electrodes forming either of the two spark gaps. 85

While the described spark plug is highly advantageous for use upon any engine, since it minimizes ignition trouble, it has a peculiar adaptation to engines possessing the defect commonly known as "oil pumping." 90 In such engines the pistons have a tendency to continually throw off lubricating oil and spark plugs of the ordinary single gap type are thus soon rendered inoperative. If the above described plug be used 95 with such engines, however, the oil will effect only the gap D and as soon as the spark is prevented from crossing said gap, the protected gap J will come into use.

What I claim as my invention is:

1. A spark plug having a chamber and openings thereinto of small area as compared to that of the chamber and having two spark gaps, one of which is formed within said chamber and the other in one 100 of said openings communicating with the chamber.

2. A spark plug comprising an insulating body, a casing receiving said insulating body, said casing forming a chamber at one 105

- end of the insulating body having an opening into the same of small area as compared to that of the chamber, and an electrode passing through the insulating body forming 5 with said electrode two spark gaps, one of which is located within said chamber and protected by such location from lubricating oil and the other of which is in the wall of said chamber.
- 10 3. A spark plug comprising an insulating body, a casing receiving said insulating body forming a chamber at one end of said

body and having a hood covering said chamber formed with openings of small area as compared to that of the chamber, 15 and an electrode passing through the insulating body forming with the casing two spark gaps, one of which is located within said chamber and is protected from lubricating oil by such location and the other of 20 which is in one of said openings of the hood.

In testimony whereof I affix my signature.

OTIS L. LONGWORTH
